UNITED STATES PATENT OFFICE.

JOSEPH THOMAS, OF BROOKLYN, NEW YORK.

MACHINE FOR SIZING HAT-BODIES.

Specification of Letters Patent No. 15,154, dated June 17, 1856.

To all whom it may concern:

Be it known that I, JOSEPH THOMAS, of Brooklyn, in the county of Kings and State of New York, have invented a new and Improved Machine for Sizing and Felting Hat-Bodies; and I do hereby declare the following to be a full and exact description thereof, reference being had to the accompanying drawings, figures, and letters of reference 10 thereon, in which—

Figure 1, is a top view of my improved machine. Fig. 2, is an end view of it. Fig. 3 is a side elevation of it.

Similar letters of reference refer to like 15 parts in all the drawings.

The nature of one part of my invention consists in an arrangement of mechanism giving the main wheel or driver a vibrating rotary motion which shall cause the material 20 to be rubbed or rolled back and forth and finally discharged by the constantly advancing movement of the main wheel.

Another part of my invention consists in so combining a circular plate or shield, and 25 table against which the material rests during the operation that the pressure is rendered perfectly adjustable.

To enable others skilled in the art to make and use my invention I will proceed to describe its construction and operation.

A, is the base of the machine.

B, B, are upright posts with a suitable brace inserted between them as shown in Fig. 2 at *j* to support and keep them firm.

C, C, are two upright posts which furnish bearings for the main wheel shaft as shown in Fig. 1.

D, is the main wheel.

E is a wheel which imparts motion to the 40 main wheel.

F, is the main shaft on which are the wheels D and E.

G is another shaft passing through the upright posts B, B, having thereon the three 45 pointed cams *y* *y*.

H and I is a forked lever one end of which is attached to the crank *z*, while the other connects with the wheel U.

J, J, are levers the lower ends of which 50 support the shaft of the wheel U, while the upper ends swing upon the shaft F.

K is a sliding carriage frame which supports a series of ratchet rollers and slides 55 freely in grooves placed upon the posts B, B, as shown in Fig. 3.

L, L, are vibrating levers with fulcrums

at (e) see Fig. 3, which work the carriage back and forth.

M, M, M, M, M, are the ratchet rollers, one of which is seen in Fig. 1, while the others are covered by the plate O.

N, N, N, N, N, are dogs or pawls which are carried upon pins as seen in Fig. 3 at (f) while the points catch in the grooves of the rollers M and cause them to rotate during 65 the motion of the carriage in one direction.

O is a table for receiving the goods as they are discharged from the machine.

P is a cross bar attached at its ends to the straps (b, b).

Q is a lever one end of which is fastened to the upright post B as a fulcrum and is also attached at the center of the cross bar P, by the bolt (a) see Fig. 2.

S is a sliding weight on the lever Q to 75 graduate the pressure upon the goods.

T is a crank wheel or pulley for propelling the wheel.

U is a small wheel which by its friction causes the wheel E to rotate.

V is a small ratchet wheel seen plainly in Fig. 3.

W is a short vibrating lever which works upon a fulcrum pin, the lower end of which is slotted to allow the stationary pin (e) to pass through it, while the upper end is furnished with a dog or pawl X for working the ratchet wheel V.

y, y, are three pointed cams which work the oscillating levers L, L.

Z is a crank placed upon the shaft G as seen in all the figures but more plainly in Fig. 3 which by its revolutions works the wheels thereby giving the motion to the main wheel or drum.

A', A', are levers having three or more arms on both sides of the wheel, which levers rock upon the main shaft F, and are slotted in their ends as shown in Fig. 3.

B', is what I call a circular adjustable 100 plate or shield, which is plainly seen in Fig. 3.

C' is an adjustable apron or plate upon which the material rests while feeding into the machine, and which is hung on pivots at 105 *i* Figs. 2 and 3.

Operation: Motion being given the wheel T, the cams y, y, will strike the levers L, L, which have fulcrum at (e) and give them an oscillating motion. The upper end of 110 these are slotted as shown in Fig. 3 and are attached to one of the ratchet rollers M',

Fig. 1, the shafts of which rollers project far enough from each side of the frame to enter the slotted levers L. As this roller M', has its bearings in the sliding carriage K, 5 it must work back and forth as the levers L oscillate. The carriage is carried back after the cams and levers have forced it forward by means of the springs (a, a,) which bear against a pin as shown in Figs. 10 2 and 3. During the travel of the carriage K, (see Figs. 2 and 3) in one direction the rollers will have no motion being held by their own friction or otherwise, but as the carriage travels in the reverse direction the 15 dogs or pawls N will catch in the ratchet grooves and cause a simultaneous movement of all the rollers and thus feed the material into the machine. Under these rollers there is an adjustable apron or table (C') Figs. 20 2 and 3 which will give the material any pressure required by altering the position of the weight on the lever a. Above these rollers there is another apron or table O which receives the goods as they are 25 discharged from the machine. On the shaft G there is a crank Z (see Fig. 3) to which is attached the forked lever H, I. In these levers is placed the shaft of the wheel U see Fig. 2:—there are two levers J, J, one on 30 each side of the wheel E, which swing on the shaft F at their upper ends, while the lower ends form the bearing of the wheel U as shown in Fig. 2. Between the lever J, on the outside of the wheel E, and the lever I, 35 there is a ratchet wheel made fast upon the shaft of the wheel U, and also a lever W, the lower end of which is slotted and inserted upon a stationary pin (c) Fig. 3 while the upper end is furnished with a dog X. As 40 the crank Z, makes its revolutions it imparts a vibratory reciprocating motion through the lever H, to the levers J, and consequently to the wheels E and U. These wheels are covered with any material to 45 produce the requisite friction upon their peripheries. During a half stroke of the crank Z, the dog X will drag over the teeth of the ratchet wheel V and thus allow the wheel U, to remain without motion; but 50 during the other half stroke the stationary pin (c) Fig. 3 will cause the dog X to catch in the ratchet wheel V, and move it forward thus giving an advance movement to the wheel U, which presses upon the wheel E

and causes it to advance and also the wheel 55 D, which is upon the same shaft.

I would here remark that the wheel D, is corrugated upon its periphery. Extending nearly around this corrugated wheel is an adjustable corrugated plate or belt B', 60 shown plainly in Fig. 3, one end of which is fastened in a suitable manner to the frame work, and is made adjustable by means of the levers A', of which there may be three or more. These levers are slotted at their 65 ends and have rods (h, h,) passing through them; and leaning against the plate B'. Passing through a hole or loop in these rods (h,) is a stop or chain which is made fast at the lower lever, and thence through the 70 other rods under the adjustable table C', to the bar or lever P where it is fastened. This bar P, is attached to a lever Q by a bolt (d). As this lever is weighted down by moving the weight S, it will draw the 75 corrugated plate closer to the wheel D, and also carry the apron C', closer to the ratchet rollers, and by this means render those parts perfectly adjustable as to pressure of the 80 material to be sized or fitted.

Having thus described my improved machine for sizing and fitting hat bodies what I claim as new therein and desire to secure by Letters Patent is:

1. I claim combining with the wheel D, 85 the wheels E and U, (or their mechanical equivalents) for giving the main wheel a vibrating motion when used with a stationary plate or bed, in order to rub the goods back and forth, and also in combination 90 therewith the mechanism for giving the main wheel the constantly advancing motion when arranged and operating in a manner substantially the same with that described.

2. I claim combining and arranging the 95 circular plate or bed, B', and table C', in such a manner that the levers A', (or their equivalents) and cords b, b, the same mechanism may adjust the plate B', to the wheel D and also the table C', to the ratchet rollers 100 and thus give any pressure desired to the goods, substantially as specified and for the purpose set forth.

JOSEPH THOMAS. [L. s.]
